UNITED STATES PATENT OFFICE.

MARSHALL C. WOODS, OF INDIANAPOLIS, INDIANA, ASSIGNOR OF ONE-HALF TO WILLIAM N. WOLFE, OF SAME PLACE.

TRACK-RAIL ATTACHMENT FOR REPLACING DERAILED CARS.

SPECIFICATION forming part of Letters Patent No. 298,437, dated May 13, 1884.

Application filed August 10, 1883. (No model.)

To all whom it may concern:

Be it known that I, MARSHALL C. WOODS, of the city of Indianapolis, county of Marion, and State of Indiana, have invented certain new and useful Improvements in Track-Rail Attachments for Replacing Derailed Cars, of which the following is a specification.

My said invention consists in an improved construction of car-replacers, principally for use in connection with combined tram and T-rails, whereby a certain and efficient replacer is provided, which is also adapted to easily and quickly perform its work.

Referring to the accompanying drawings, which are made a part hereof, and on which similar letters of reference indicate similar parts, Figure 1 is a plan view of a portion of a street-railway provided with my improvement; Fig. 2 a detail view on an enlarged scale 20 of a portion of two of the rails thereof, where they come together; and Fig. 3, a cross-section of the same on the dotted line z z.

In said drawings, the portions marked A represent the rail, and B a peculiarly-constructed fish-plate, which forms the main part of my improved car-replacer. The rail A may be any suitable form of a combined tram and T rail for use in a street-railway. The particular form shown is reserved as the subject matter of a future application for Letters Patent. In its top face at the points where it is desired to have the car-replacers—usually at the end of the rail—it is provided with longitudinal grooves a', which catch the flange of the wheel as it comes upon the track and prevent it from immediately sliding off again before the draft can be changed, so as to naturally draw the car into proper position on the track. There are preferably two of these 40 grooves, as shown—one near the outer edge of the rail and another nearer the inner edge—and a double assurance is provided against the failure of the replacer to do its work.

The combined fish-plate and car-replacer B should be of steel, in order that it may endure the excessive wear which will come upon its edges; but it may be of any suitable material. Its top edge, a, comes up flush with the top of

the rail, as shown, its outer edge being somewhat longer than the part which bears directly against the rail at its top edge, thus forming a notch between the top corners of the fish-plate and the edge of the rail, and thereby adapting it to more readily catch the flange of the car-wheel and guide said wheel upon the track.

The operation of my invention is as follows: When a car becomes derailed, it is pulled along until the wheels come in contact with the projection a of the combined fish-plate and car-replacer, when they will run up on said projections and be guided onto the rail, the flanges of said wheels engaging with the longitudinal grooves a', and the wheel thus steadied until the draft can be changed to pull the car onto the track, when the wheels will at once become 6 replaced, and the car is thus restored to a position to proceed on its way.

Having thus fully described my said invention, what I claim as new, and desire to secure by Letters Patent, is—

1. The combination of the rail A, provided with longitudinal grooves a' and the car-replacer B, the top edge, a, of which extends up flush with the top of the rail, whereby it is adapted to guide the wheel of a derailed car 75 back onto the track, substantially as set forth.

2. The combination, with the rail A, having longitudinal grooves a' in its face, of the combined fish-plate and car-replacer B, the top edge, a, of which extends up flush with the top 80 of the rail, and is constructed to form notches at the ends of said edge alongside the rail, substantially as described, and for the purposes specified.

3. The combination, with a car replacer, of the rail A, having longitudinal grooves a' in its face, whereby said car-replacer is aided in performing its function, substantially as set forth.

In witness whereof I have hereunto set my hand and seal, at Indianapolis, Indiana, this 90 7th day of August, A. D. 1883.

MARSHALL C. WOODS. [L. S.]

In presence of—

E. W. BRADFORD,
CHAS. L. THURBER.
